UNITED STATES PATENT OFFICE.

GIUSEPPE BECCARI, OF FLORENCE, ITALY.

PYRE FOR THE MANUFACTURE OF CHARCOAL.

1,319,688.

Specification of Letters Patent.

Patented Oct. 28, 1919.

Application filed August 26, 1918. Serial No. 251,400.

To all whom it may concern:

Be it known that I, GIUSEPPE BECCARI, a subject of the King of Italy, residing at Florence, Italy, have invented new and useful 5 Improvements in Pyres for the Manufacture of Charcoal, of which the following is a specification.

The "pyre" for the manufacture of charcoal is a continuous-action oven serving for 10 the carbonization of wood.

Figure 1 represents a front view, partly in section, of the arrangement of a battery comprising four "pyres." Fig. 2 also represents the plan of said battery, partly in 15 section. There may be any number of batteries. Figs. 3, 4 and 5 are detail views of one form of regulator embodying my invention.

Each battery consists in a chamber of suitable shape and dimensions, built of fire- 20 bricks, of refractory material or of any other appropriate material. The lower part of the chamber may be in the form of a hopper —b— and provided with a closing device —c— having a sand-bath or a bath 25 of any other description. It is advisable for this closing device to have a valve —d— for regulating the admission of air. The chamber —a— contains, at convenient points, grates —e— and —f—; at its top 30 and side respectively, it is furnished with charging ports —g— and —h—, and with an aperture —i— communicating with the conduit for the smoke and the fumes developed by the carbonization of the wood.

35 At its lower part, it is advisable for the "pyre" to have a sub-passage —l— to facilitate the discharge of the charcoal from the chamber —a— and in order to conveniently regulate the admission of the air necessary 40 to carbonization. In the front wall of the chamber —a— are pierced holes —m— furnished with appropriate lids or stoppers to enable the observation of the internal 45 progress of the carbonization and for the admission to the zones of carbonization of air in the quantity strictly necessary for perfect carbonization; in said wall there are various narrow openings —n— or small low windows for setting in position the bars 50 of the grates —e— —f—, or for removing the same in due course.

The "pyre" may be provided with a vapor-condensing apparatus —o— which may be of various shapes and dimensions 55 and furnished with a regulator —p— for the escape of smoke from the chamber —a—.

As shown in Figs. 3, 4, and 5, the regulator —p— comprises an inner circular casing 10 fixed to the vapor condenser —o— and provided with an opening 11. Surrounding 60 the casing 10 is a rotatable shutter 12 formed with an opening 13 which is adapted to register with the opening 11, as shown in Fig. 4. By rotating the shutter 12 through the handle 14, the position of the 65 opening 13 is adjusted to vary the opening 11, thus controlling the escape of smoke, as will be understood.

Having described the "pyre" we will now state its mode of working. At the commencement of the operation, kindling consisting in straw, twigs or dry chips should be placed on the grate —c— situated above the hopper; on the top of said kindling are placed the pieces of wood to be carbonized, 70 through the charging ports —g— —h—. After the chamber —a— has been filled, said ports —g— and —h— are closed whereupon the regulator —d— located at the bottom of the hopper is opened as well 75 as the regulator —p— belonging to the condenser —o—. After this has been done, the kindling is set fire to, and when it has begun to light the wood to be carbonized situated in the lower part of the chamber, 80 the admission of air is lessened and regulated by means of the valve —d—, the regulator —p—, the holes —m— and the bars —e— of the grates, in such manner as to obtain the carbonization of the wood at a 85 dark heat and not at a red heat.

After a certain time, the wood partially carbonized in the lower part of the chamber —a— decreases in volume; then fresh wood is introduced through the charging 95 port —g—. When the material inclosed between the two grates is completely carbonized, it may be removed. To effect this, the regulator —p— of the condenser —o— is closed, a vessel containing water being 100 drawn into the sub-passage —l—, which vessel may be provided with a cage introduced into it; said vessel —k— may be conveyed on wheels.

After the vessel has been placed underneath the hopper —b— the bars of the grate —c— are removed and the closing device —d— is opened. The charcoal inclosed between the two grates —e— —f— falls into the vessel —k— containing the water, it 110 is quenched and immediately removed by raising the cage which held it. After this

has been done with some celerity, the hopper —*b*— is re-closed and the bars of grate —*e*— replaced in position; the bars of the upper grate —*f*— are removed. The wood 5 which is uppermost, partially carbonized, descends and rests on the bars of grate —*e*—. After this has been effected, the regulator —*p*— of the condenser —*o*— is re-opened to the requisite extent, the admission of air 10 is regulated in the usual way by means of the special regulators already indicated, fresh wood to be carbonized is placed in the chamber and this manner of proceeding insures the constant and continuous production of charcoal.

A similar arrangement on a conveniently reduced scale may serve for domestic purposes, for heating and for obtaining charcoal.

20 Claims:

1. An apparatus for manufacturing charcoal comprising a kiln having a plurality of chambers formed therein, a vapor condenser above the chambers and commun-

cating therewith, a regulator for said condenser, a pair of grates removably fitted in each of said chambers and spaced apart to provide two compartments in each chamber, a hopper at the bottom of each chamber, doors for closing the lower end of the 25 hoppers, an air valve, in each door, and passageways formed in the kiln below said hoppers to accommodate receptacles.

2. An apparatus for manufacturing charcoal comprising a kiln having a chamber 30 formed therein, a condenser on the kiln, a passage formed in the kiln and connecting the chamber and condenser, a pair of superposed grates in the chamber, said grates being removable laterally from the chamber, a hopper at the lower end of the chamber, a door for the hopper, an air valve 35 in said door, and a passageway formed in the kiln below the hopper for accommodating a receptacle.

In testimony whereof I have signed my name to this specification.

GIUSEPPE BECCARI.
